BELT HOLDER

Herman W. Suttle, 109 Broadmoor Drive,
Jackson, Miss.

Filed Oct. 20, 1965, Ser. No. 87,648

Term of patent 14 years

(Cl. D80—8)

The fragmentary broken line representation of a garment hanger in FIGURES 2 and 3 is for purposes of illustration only.

I claim:

The ornamental design for a belt holder, substantially as shown and described.
